UNITED STATES PATENT OFFICE

REUBEN N. TRANE, OF LA CROSSE, WISCONSIN

HUMIDIFIER

Application filed November 8, 1928. Serial No. 318,000.

My invention relates to humidifiers for use in combination with air fin type radiators, and an object is to provide an efficient means for supplying moisture to the air in the rooms 5 containing the radiators. The former type of humidifier was objectionable because it consisted of an unsightly object on top of or connected with an equally unsightly cast iron radiator. Another object of my invention is 10 to provide a humidifier which together with the radiator is contained in an enclosure concealing both radiator and humidifier from sight.

Another object of my invention is to provide 15 a humidifier which will supply moisture to the air with a minimum loss of efficiency of the radiator.

Another object of my invention is to provide means whereby all the troughs of a humidifier on any floor level may be automatically kept filled with water to any desired degree.

Another object of my invention is to provide 25 a humidifier which will work efficiently in connection with a radiator as is described in my application No. 104,196 filed April 23, 1926, relating to radiators.

Another object of my invention is to provide 30 a humidifier which will remain clean a maximum length of time.

Another object of my invention is to provide a particular shape of wicking which may be easily and readily removed and replaced.

The full objects and advantages of my invention will appear in connection with the 35 detailed description, and the novel features embodied in my inventive idea will be particularly pointed out in the claims.

Referring to the drawings which illustrate 40 the application of my invention in one form, Fig. 1 of the drawings illustrates an isometric view of the device having two of the walls of the enclosure or heat cabinet broken away for the purpose of illustrating an isometric view 45 of the humidifier mounted on an air fin type radiator and all contained in the enclosure.

Fig. 2 illustrates an end elevation of the 50 humidifier.

Fig. 3 illustrates a side elevation of the humidifier.

Fig. 4 illustrates a section of wick material before folding into a wick sheet.

Fig. 5 illustrates a view of the wicking material after the first operation of folding.

Fig. 6 illustrates a view of the wicking material after the second operation of folding. 55

Fig. 7 illustrates the wicking folded into a sheet and supporting legs.

Fig. 8 illustrates a diagrammatic view of 60 part of a heating system showing a method of automatically filling the water troughs of the humidifier.

Fig. 9 illustrates an isometric view of the 65 device showing the auxiliary water pan with means for filling and emptying the water pan, and a water pan being an integral part of the radiator.

Figure 10 is a perspective view of the 70 water pan showing the apertures 12A through which the wicking legs depend.

Referring to Fig. 1, the air fin type radiator (1) is composed of a multiplicity of heat tubes (2) on which are mounted a multiplicity of fins (3), all of which are contained in a heat cabinet (4). The heating is done by 75 convection, the cold air being drawn by convection into the bottom of the heat cabinet (4) in the direction of the arrows (5) through the fin type radiator and out of the opening (6) at the top of the heat cabinet 80 which is hinged at (30).

The humidifier comprising two long parallel troughs (7) and the wicking (8) are mounted on the air fin type radiator (1), 85 preferably on the side walls of the radiator so as not to interfere with the flow of air currents through the radiator. The troughs (7) may be of any desired length preferably the length of the radiator and are preferably narrow to better hold the wicking and deep enough to contain sufficient water for evaporation purposes. In the method shown in Fig. 9 the side (11) of the trough (7) is also the side of the air fin radiator (1) which reduces the cost of manufacture and solves 95 the problem of attaching the troughs to the radiator in such manner as not to impede the flow of air through the radiator.

The sheets (9) and the legs (10) are stabilized and held in the same general plane as 100

the fins (3). This may be accomplished in a number of methods but I prefer to insert the legs (10) into grooves (31) formed by the corrugations (32) in the wall of water pan (7), as shown in Fig. 3. Another method I have used is to insert the legs (10) into apertures (12) through a cover (12a) to the trough (7), as shown in Fig. 9.

The sheets (9) are thus held in an upright position in the same general plane as the fins of the radiator, thereby impeding as little as possible the flow of the air currents through the heat cabinet and at the same time presenting a large extended surface to the air currents for the evaporation of moisture.

The wicking sheets (9) supported by the wicking legs (10) are preferably made in the following manner: A sheet of blotting paper or other absorbent material, shown as (20) in Fig. 4, has the square apertures A and B cut in the material, which is then folded double on the line CD making a form shown as (21) in Fig. 5, which is folded on the lines EF and GH, making a form shown as (22) in Fig. 6, which is further folded on the lines IJ and KL, which is shown as (23) in Fig. 7, comprising a wicking sheet (9) and the legs (10). It will be apparent that the wicking sheet (9) is composed of two thicknesses of the wicking material in the form of a sheet and that the legs are composed of four thicknesses of the wicking material and support the wicking sheet (9). The wicking leg (10) may again be folded to give further rigidity to the leg (10), in which case the leg (10) would have eight thicknesses to two thicknesses of the sheet. Both the wicking legs and sheet may be stapled together to give further rigidity. The capillary attraction of the water up the legs (10) moistens the sheet (9) and the moisture is evaporated by the air currents rising from the radiator.

Referring to Fig. 8 which is a diagrammatic layout of a part of a heating system on one floor, it will be observed I have provided for an automatic filling of the water pans. A water supply pipe (14) is connected to an auxiliary covered water pan (15), the inflow of the water being controlled by the conventional float and valve (16).

The water pan (15) is on the same level as the water pans in humidifiers on the same floor or level so that the rise of water in the water pan (15) above any predetermined level will cause the float and valve (16) to shut off the water, thus the water pans in the humidifiers will be kept filled to the level of the water in the water pan (15) through the pipe (18).

I have also provided an overflow pipe (17) to prevent any overflow of water in the water pans in the humidifier. I have also provided a shut-off valve (19) to shut off all water to the water pans.

At the outlet of the pipe (18) in the water

pan (15) I have provided an adjustable sleeve (24) which slides upon the pipe (18) so that upon the lowering or raising of the sleeve (24) the level of the water in the pan (15) and also in the water pans on the radiators will correspond to the height of the adjusted sleeve. Another means of adjusting the level of the water in the water pans on the radiators is by means of the adjustable screws (25), Fig. 1, which are fastened to each end of the bottom of the container (7) or may be adjusted to raise or lower the container (7) in accordance with floor levels and to allow for differences in the pitch of floor. Where it is impractical to use the automatic device for filling the water pan (7), I have further devised an auxiliary water pan (26) which is connected with the pans (7) by means of the T pipe (27). From the side of the auxiliary pan (26) I have a pipe which extends outside of the cabinet, the top of which is level with the top of the pan (26). This pipe (28) is for the purpose of filling the tank (26) to the top of the level of the tank (26). At the bottom of the pipe (28) I have placed a petcock (29) for the purpose of letting the water out of the water pan (26) when it is desired that this be done.

While I have described in detail a preferred embodiment of my invention, it is understood that I am not limited to the details therein set forth except as defined by the following claims.

I claim:

1. In a humidifier adapted to be secured in a casing above a radiator having air fins, parallel elongated water pans mounted on the side of said radiator, a cover to the water pan with apertures therein, wicking sheets and wicking legs mounted in the same planes as the radiator fins, said wicking sheets and legs being maintained in the same planes as the radiator fins by inserting the wicking legs into the water pans through the apertures in the water pan covers.

2. In a humidifier adapted to be secured in a casing above a radiator, having air fins, the combination of a water pan, wicking sheets mounted in substantially the same planes as the radiator fins, wicking legs supporting the said wicking sheets, said wicking legs depending in said water pan.

3. In a humidifier adapted to be secured in a casing above a radiator having air fins, the combination of a water pan, wicking sheets mounted in substantially the same planes as the radiator fins, wicking legs supporting the wicking sheets, said wicking legs depending in said water pan, said casing having an air inlet at the bottom, an air outlet at the top, and means outside the casing to fill and empty the water pan.

4. In a humidifier adapted to be secured in a casing above a radiator having air fins, the combination of a water pan, wicking sheets

mounted in substantially the same planes as the radiator fins, wicking legs supporting the wicking sheets, said wicking legs depending in said water pan, and means to adjust the 5 water level in the water pan.

5. In a humidifier adapted to be secured in a casing above a radiator having air fins, the combination of a water pan, wicking sheets mounted in substantially the same 10 planes as the radiator fins, said wicking sheet having legs depending in said water pan and supporting the wicking sheets, the said wicking legs being thicker than the wicking sheets.

15 6. In a humidifier adapted to be secured in a casing above a radiator having air fins, the combination of water pans mounted on the sides of the radiator, wicking sheets and wicking legs mounted in substantially the 20 same planes as the radiator fins, said wicking legs depending into the said water pans, the casing enclosing the radiator and the humidifier.

In witness whereof, I hereunto subscribe my
25 name this 19 day of October, 1928.

REUBEN N. TRANE.
